(57) **CLAIM**

The ornamental design for temporary support stand for a volumetric modular unit, as shown and described.

DESCRIPTION

FIG. 1 is a perspective view of a temporary support stand for a volumetric modular unit showing a new design;

FIG. 2 is a top view thereof;

FIG. 3 is a bottom view thereof;

FIG. 4 is a left side view thereof with the right side view being a mirror image;

FIG. 5 is a front view thereof with the rear view being a mirror image;

FIG. 6 is a section view thereof taken along line 6-6 in FIG. 5;

FIG. 7 is an enlarged view thereof taken along line 7-7 in FIG. 6; and,

FIG. 8 is an in-use view thereof.

The broken lines in the Figures show portions of the temporary support stand for a volumetric modular unit and environment which form no part of the claimed design.
